UNITED STATES PATENT OFFICE

2,366,510

RIVET STRING

Louis Frank, Fellows, Calif., assignor of one-third
to Adolph Reader, Taft, Calif.

Application February 22, 1943, Serial No. 476,742

1 Claim. (Cl. 85—37)

My invention relates to string rivets, i. e., a series of axially aligned connected rivets and the principal object of my invention is, to arrange and connect a plurality of rivets in string or rod form, so as to greatly expedite the work attending the handling of the rivets, particularly the driving and setting of the same in the work.

A further object of my invention is to arrange and connect rivets so that the same may be conveniently handled by an appliance such as a rivet gun, which operates rapidly and accurately in driving, severing and setting the rivets, thereby effecting a material saving of time, labor and consequent expense in rivet setting operations.

A further object of my invention is, to directly connect the end of the shank of one rivet to the head of the next adjacent rivet by means of a short neck of small diameter and to form in said neck a circumferential groove, for the accommodation and to facilitate the action of the severing means forming a part of the rivet setting gun or tool.

A further object of my invention is, to provide a simple and practical connection between the ends of the strings of connected rivets, thus enabling one string to readily, and without interruption, follow another, through the feeding mechanism of the rivet gun.

With the foregoing and other objects in view, my invention consists in certain novel features of construction and arrangement of parts that will be hereinafter more fully described and claimed and illustrated in the accompanying drawing in which:

Fig. 1 is a side elevational view of a string or series of rivets assembled and connected in accordance with my invention.

Fig. 2 is an elevational view of a portion of a rivet string made up of a series of flat headed rivets.

Fig. 3 is an enlarged cross section taken on the line 3—3 of Fig. 2.

Fig. 4 is an elevational view of a plurality of connected round headed rivets.

Fig. 5 is an elevational view partly in section of a pair of connected rivets having concave heads.

Fig. 6 is an elevational view of a portion of a string made up of rivets having conical heads.

Fig. 7 is an elevational view of a portion of a string composed of rivets having truncated conical heads.

Fig. 8 is an elevational view partly in section and showing a plurality of connected rivets having tubular shanks.

Fig. 9 is a cross section taken on the line 9—9 of Fig. 8.

Fig. 10 is an elevational view of a pair of connected rivets having shanks that are square in cross section.

Fig. 11 is a cross section taken on the line 11—11 of Fig. 10.

Fig. 12 is an elevational view partly in section and showing the connection between the ends of the rivet strings.

Fig. 13 is a detail sectional view showing one of the end rivets of a string set in the work.

Fig. 14 is an elevational view of a portion of a string of screws assembled and connected in accordance with my invention.

Referring by numerals to the accompanying drawing and particularly to the construction illustrated in Figs. 1, 12 and 13, 10, 10 designates the shank or body portions of rivets having flat heads 11, said rivets being arranged end to end in axial alignment, with the end of the shank of each rivet connected to the center of the head of the next adjacent rivet by an axially disposed short neck 12 of small diameter.

The string of rivets thus formed is capable of being expeditiously driven and set by a rivet gun inasmuch as the handling of the individual rivets is entirely eliminated.

In order to connect the ends of the strings so that same will feed continuously through the rivet guns, a small axially disposed pin 10^a is formed on the end of the shank of the rivet at one end of the string and for the accommodation of the severing means, of the rivet gun, a small circumferential groove is formed in the pin adjacent the end of the shank.

Formed in the head of the rivet at the opposite end of the string, is an axial recess 11^a for the reception of that portion of the pin 10^a beyond the groove 10^b and thus the strings of rivets may be connected prior to their delivery to the rivet gun or setting implement, so as to enable the driving and setting functions to be carried on continuously.

When the last rivet of each string is driven and set in the work, the severed end of the pin 10^a remains in the recess 11^a and is retained therein by the edge of the metal in the head that is riveted inward over the end of said pin, during the hammering action of the rivet gun (see Fig. 13).

It is to be understood that the necks 12 in the form of string illustrated in Fig. 1 may, if desired, be formed with circumferential grooves such as 10^b, for the accommodation of the severing means of the rivet gun.

In Figs. 2 and 3 the rivet shanks 13 are provided with flat heads 14 and each shank is connected to the head of the next adjacent rivet by a small short axially disposed neck 15.

In Fig. 4 the rivets comprising shanks 16 and round heads 17 are connected by short axially disposed necks 18.

In Fig. 5 the rivets composed of shanks 19 and heads 20 having concave outer faces 20^a are connected by short axially disposed necks 21.

In Fig. 6, the rivet shanks 22 are provided with conical heads 23 and are connected by short axially disposed necks 24.

In Fig. 7 the rivets comprising shanks 26' and truncated conical heads 27', are connected by short necks 28.

In Figs. 8 and 9 the rivets have tubular shanks 25 with rounded heads 26 and connecting the end of each shank with the head of the next adjacent rivet are one or more short necks 27.

In rivets 10 and 11 the rivet shanks 29 are square or non-circular in cross section with flat heads 30 and a short neck 31 connecting the end of each shank with the head of the next adjacent rivet.

In Fig. 14 I have shown a string of screws arranged end to end with the end of the threaded shank 32 of each screw connected to the center of the head 33 of the next adjacent screw, and the same connection may be utilized between nails, tacks and the like.

Groove 10^b may be located on neck 12 at the point where same joins the end of the rivet shank

or at any distance away from said end. Further, said groove may be formed on the necks 27 of the tubular rivets.

Thus it will be seen that I have provided rivet strings which are simple in construction, inexpensive of manufacture and very effective in performing the functions for which they are intended, viz., the rapid and convenient handling of rivets while the same are being driven and set with a rivet gun or similar implement.

It will be understood that minor changes in the size, form and construction of the various parts of my improved rivet strings may be made and substituted for those herein shown and described without departing from the spirit of the invention, the scope of which is set forth in the appended claim.

I claim as my invention:

As a new article of manufacture, a rivet string comprising a row of axially aligned connected rivets, a pin projecting from the end of the shank of the rivet at one end of the string there being a circumferential groove formed in each pin intermediate its ends and there being a pin-receiving recess formed in the head of the rivet at the other end of the string the length of which recess is greater than the length of that portion of the pin beyond the groove, so that said portion will be wholly embedded in the rivet head when said portion is severed from the remaining portion of the pin and the rivet is set.

LOUIS FRANK.
